CLAIM

The ornamental design for a LED track luminaire, as shown and described.

DESCRIPTION

FIG. 1 is a perspective view of a LED track luminaire; FIG. 2 is a front view thereof of the LED track luminaire, wherein a rear view is the mirror image;

FIG. 3 is a first side view thereof taken ninety degrees from the front view of the LED track luminaire, wherein a second side view is a mirror image thereof;

FIG. 4 is a bottom view thereof of the LED track luminaire;

FIG. 5 is a top view thereof of the LED track luminaire;

FIG. 6 is a perspective view of the LED track luminaire of FIGS. 1-5, but shown in an alternate position or configuration;

FIG. 7 is a front view thereof of the alternate position or configuration of FIG. 6, wherein a rear view is the mirror image;

FIG. 8 is a second side view thereof taken ninety degrees from the front view of the alternate position or configuration of FIG. 6, wherein a second side view is a mirror image thereof;

FIG. 9 is a bottom top view thereof of the alternate position or configuration of FIG. 6; and,

FIG. 10 is a top view thereof of the alternate position or configuration of FIG. 6.

The broken lines in the drawings are for illustrative purposes only and form no part of the claimed design. In addition, any shading forms no part of the claimed design and is provided to illustrate contour only and is not an indication of texture, gloss, and the like.

1 Claim, 8 Drawing Sheets
